(57) **CLAIM**

The ornamental design of a portion of a yoked headgear, as shown and described.

DESCRIPTION

FIG. 1 is a perspective view of a first embodiment of a portion of a yoked headgear showing our design;

FIG. 2 is a front view thereof;

FIG. 3 is a rear view thereof;

FIG. 4 is a perspective view of a second embodiment of a portion of a yoked headgear showing our design;

FIG. 5 is a front view thereof; and,

FIG. 6 is a rear view thereof.

Where included, broken (dot/dash) lines showing environment or structure are for illustrative purposes only and form no part of the claimed design.

The use of stippled shading and line shading is used to indicate contrasting materials.

The dashed lines in FIGS. 1–6 are representative of stitching.
